UNITED STATES PATENT OFFICE.

DAVID WM. WEISER, OF DUPONT, OHIO.

WIRE FENCE.

SPECIFICATION forming part of Letters Patent No. 436,279, dated September 9, 1890.

Application filed December 10, 1889. Serial No. 333,256. (No model.)

To all whom it may concern:

Be it known that I, DAVID WM. WEISER, a citizen of the United States, residing at Du-
pont, in the county of Putnam and State of
Ohio, have invented certain new and useful
5 Improvements in Wire Fences; and I do hereby declare the following to be a full, clear,
and exact description of the invention, such as
will enable others skilled in the art to which it
10 appertains to make and use the same.

The object of my invention is to produce a
cheap, secure, and durable wire fence; and it
consists in the matters hereinafter described
and pointed out in the claims.

15 In the accompanying drawings, Figure 1 is
a side elevation of several panels of my im-
proved fence, the diameter of the post being
exaggerated with respect to its height for
clearness of illustration. Fig. 2 is a perspec-
20 tive of a single post-supporting section of
wire and the wire fastenings therefor. Fig. 3
is a detail of one form of fastening. Fig. 4 is a horizontal section of a post on an enlarged
scale.

25 I make the posts 1 of iron rods about one-
half inch in diameter and set them in blocks 2,
of wood or stone, about one and a half feet
wide, three feet long, and seven inches thick,
the length of the blocks being placed crosswise
30 of the fence. These blocks can also be made
each partly of iron and the rest of wood, or
they may be made of concrete or any suitable
material. Four and a half to five feet is a
suitable length for the posts if the blocks are
35 placed with their upper surfaces on a level
with the top of the ground, as I generally prefer.
The posts may be set about eight feet
apart and braced, as indicated at 3, once in
forty-eight feet, or oftener.

40 The body or intermediate part of each line-
wire is secured to the posts by inserting it in
a crescent-shaped cut or kerf 4, and then
twisting transversely about the post and line-
wire at their junction one or more binding-
45 wires 5, said wires also resting in the cut or
groove. After the binding-wire is passed
about the post and line-wire its ends are
brought together and tightly twisted, thereby
drawing all parts of it in close contact with
50 the parts to be bound.

Bands for analogous uses are not new, but

heretofore they have not been applied in a
manner to prevent them from becoming loose
or from being moved on the posts by the weight
of wires, or by the rubbing of animals, or in 55
other ways.

In my construction each line-wire rests
upon a shoulder at the bottom of the cut near
its deepest point and has thereon a vertical
support, and it is securely held upon this seat 60
by the binding-wires, both wires being solidly
held by the clinch of a lip 6, formed when the
groove is made, which lip is forced down upon
them. Thus bound and held, the wires are
not liable to be moved out of place, the cut or 65
groove formed in the post being of peculiar
shape and especially adapted to form a bed
or seat for both wires. This groove is pro-
duced by an approximately crescent-shaped
70 tool, which is forced upon and into the sur-
face of the post in a downward direction,
thereby producing a cut substantially as in-
dicated in the drawings. As will be seen, it
extends around the post in a downward di-
rection, so that the line-wire may rest in it at 75
its center or deepest part, and the binding-
wire at or near its extremity 7. The groove
is therefore adapted to receive both wires, and
its form is such that it does not unnecessarily
weaken the post, as would an ordinary cut, or
80 such as would be made by a straight-edged
tool.

Two binding-wires may be employed, as
shown in Fig. 1. In such case the groove or
cut is formed to be symmetrically disposed
about the post, its extremities 7 both being
directed as shown in Fig. 1. Each binding-
85 wire in such construction rests in an extrem-
ity 7 of the groove at the side of the post and
both are supported and fastened therein. If
but one binding-wire were employed, it would
of course lie in it on one side only of the
post. To give a single binding-wire a seat
in the groove on both sides of the post, it may
be cut, as indicated in Fig. 2, obliquely with
95 one extremity above the line-wire and with
the other on the opposite side of the post be-
low the same. In such construction the bind-
ing-wire will be provided with a depressed
seat on both sides of the post, one above and
100 one below the seat of the line-wire. When
the wires have been bound in place by twist-

ing the binding-wire or binding-wires, the raised lip of the groove is forced or swaged down upon them substantially as shown, thereby effectually obviating all danger of 5 the wires slipping on the post. Such slipping is highly objectionable, and is very liable to occur unless thoroughly guarded against, as by my improvement, which, as before stated, obviates the evil and without the necessity 10 of weakening the post excessively, as would be the case by a single straight cut sufficient to form a seat both for the line and binding wires.

8 indicates a coupling-plate perforated to 15 receive the ends of line-wires which are to be secured therein, and 9 indicates wire couplings for a similar purpose, and either form can be employed, though the plate is preferred, except at a fence-corner. A cut, sub- 20 stantially as above set forth, except that it is made horizontal, or nearly so, is formed at a proper point on the post. The plate is then slipped over the top of the post and moved down, so as to rest in the seat thereby formed.

25 In Fig. 1 is shown a means of securing it firmly in a seat. Downward cuts are formed on one or both sides of the post adapted to receive the downturned edges 10 of the plate, and such edges are firmly secured by forcing 30 or swaging the lips of the cut down upon the flanges. The wire couplings are secured in similar manner. When the lower plate has been thus secured, suitable cuts or grooves for each higher coupling can be made and 35 the plate or wire couplings similarly secured therein. 11 indicates a rail which is placed on the upper end of the posts, the ends of the rails being fitted to the posts and the ends to each other and spliced, substantially as re- 40 presented. This rail is made with a down- turned flange, or with two such flanges, as represented, one or both of which may be supported by a lip raised by cutting the post, which lip, if desired, can be swaged down 45 upon the flange. The head of the post will ordinarily be upset sufficiently to prevent the rail from being lifted off the post, and the above-described lip prevents its descent thereon.

50 A fence can be cheaply constructed as above described which will withstand the action of winds and frosts and the ordinary rubbing of cattle without vertical displacement of the wires, and which will be very suitable for 55 most of the uses of such structure.

Heretofore fence-wires have been secured to angular posts by swaging, and such construction is not broadly of my invention. The present improvement applies to cylin- 60 drical posts in which it is difficult to produce a sufficient kerf or slot to securely hold a wire without unduly weakening the post. If the kerf or cut be made sufficiently large to embrace the whole wire with certainty at every 65 point of contact, a small or moderate-sized

post of cylindrical cross-section is impracticable. On the other hand, if a fastening-wire alone be used, it, together with the line-wire, is liable to slip down and also be rubbed or borne up or down on such post. My improvement utilizes both the kerf (or swaging) and the wire, the former serving as a vertical support for both the line and binding wires. The binding-wire serves to prevent the displacing of the line-wire, even though the swaging is in some instances insufficient or defective, and as it also enters the kerf or notch it is thereby securely held from being moved either up or down by the rubbing of stock or the thrusting of heads or bodies between the wires or the climbing of persons. My slot, of approximately crescent shape or some equivalent, is required to prevent the displacement of the binding-wire. As in effect stated, the slot or swaging alone is not sufficient, and particularly in the case of posts made of comparatively small cylindrical rods, because of the liability of the line-wires to be lifted out of the same by force when it is accidentally defective in manufacture or when the force applied is sufficient in the absence of such defect; and the binding-wire alone is insufficient, particularly on posts such as described, from its liability to slip; and, furthermore, it would not act efficiently to prevent slip in case of the failure of the swaging, unless it was entered into a slot or notch in the post, as by my improvement.

Having thus described my invention, what I desire to secure by Letters Patent is—

1. In a fence, the posts made of rods and provided with lips near their tops, in combination with rails having downturned flanges embracing the sides of the post and resting on lips formed by cuts in the post, said lips being swaged upon the flanges, substantially as set forth.

2. In a fence, a cylindrical post provided with a crescent-shaped groove, a line-wire resting on a seat midway between the ends of the groove, and bound by wires that also rest in the same groove at its ends and on each side of the post, the several wires being held by the lip of the groove compressed upon them, substantially as set forth.

3. In a fence, a line-wire resting in a seat formed by an oblique groove, the extremities of which are one above and the other below said line-wire, and bound by a wire resting in said groove on two sides of the post, both above and below the line-wire, substantially as set forth.

In testimony whereof I affix my signature in presence of two witnesses.

DAVID WM. WEISER.
